DESIGN FOR A FUR COLLAR

David Feld, New York, N. Y.

Application July 31, 1940, Serial No. 94,052

Term of patent 3½ years

To all whom it may concern:

Be it known that I, David Feld, a citizen of the United States of America, residing in New York city, in the Borough of Manhattan, county and State of New York, have invented a new, original, and ornamental Design for a Fur Collar, of which the following is a specification, reference being had to the accompanying drawing, forming part thereof, wherein,

I claim:

The ornamental design for a fur collar, as shown.

DAVID FELD.
